UNITED STATES PATENT OFFICE.

JOHN W. JEPSON, OF DEPEW, NEW YORK, ASSIGNOR TO GOULD COUPLER COMPANY,
A CORPORATION OF NEW YORK.

ENGINE APPLIANCE.

1,240,725.

Specification of Letters Patent. Patented Sept. 18, 1917.

Application filed August 13, 1912. Serial No. 714,775.

To all whom it may concern:

Be it known that I, JOHN W. JEPSON, a citizen of the United States, and a resident of Depew, county of Erie, and State of New York, have invented certain new and useful Improvements in Engine Appliances, of which the following is a specification.

My invention relates to engine appliances and more particularly to arrangements including an internal combustion engine and storage battery and dynamo electric apparatus so arranged that the dynamo electric apparatus may be used for transmitting energy from the engine to charge the battery and from the battery to start the engine.

The main object of my invention is to provide a simple arrangement for this purpose in which the engine may be easily started with the employment of a minimum amount of energy and in which the interchange or change of gears for this purpose is rendered unnecessary. Further objects, features and advantages will more clearly appear from the detailed description given below taken in connection with the accompanying drawing which shows a diagram illustrating an arrangement embodying my improvements in one form.

Referring to the drawing, 1-1 represent cylinders of an internal combustion engine of the gas engine type in which operate pistons 2-2 operatively connected with the engine shaft 3. Secured on the shaft 3 is a gear 4 driving an intermediate gear 5 which in turn drives a gear 6 on shaft 7. Driven by shaft 7 is a pump 8 for the purpose of circulating the cooling water for the engine. Also secured to the shaft 7 is the armature 9 of a dynamo, which is provided with two sets of armature windings connected respectively to commutators 10 and 11. 12 represents a set of shunt field windings for the dynamo, and 13 a set of series field windings therefor. 14 represents a storage battery in operative relation to the dynamo electric apparatus and having lamp or other translating devices 15 connected across the terminals by conductors 16. 17 represents a main switch connected in series between the battery and dynamo electric apparatus and provided with a shunt operating coil 18 and a reverse series coil 19, the switch operating in any usual or well known man-

ner. 20 represents a switch for connecting the shunt windings 12 across the circuit.

55

The dynamo is also provided with alternating current terminals 21 which feed an alternating current circuit 22 having in series therein the primary of a transformer 23. Connected in series with the circuit 22 is 60 also a timing device 24 of any well known sort. The cylinders 1-1 of the engine are provided with jump spark devices 25 which are connected by conductors 26 with a distributor 27 of any well known kind, and 65 the secondary of the transformer 23 has one terminal thereof connected to the distributor 27 while the other terminal is grounded to the engine by conductor 28.

In order to provide an arrangement 70 whereby the dynamo electric apparatus may supply sufficient voltage to supply the battery when being driven by the engine and in which the dynamo electric apparatus may have sufficient torque to start the engine 75 when supplied from the battery, I provide switching means for connecting the two sets of armature windings in series when charging the battery and in parallel when it is desired to start the engine. These switching means also connect the series field 13 to oppose the shunt field 12 when charging the battery, but aid the shunt field 12 when starting the engine. For this purpose a multiple pole switch having three arms 30, 80 31 and 32, is provided which arms are adapted to make contact respectively with contacts 33, 34 and 35. The arms 30, 31 and 32 are connected by a link member 36 for simultaneously operating the same.

85

90

When the arms are in the position shown in full lines the apparatus is connected for starting the engine by energy transmitted from the battery. In such case the direction of current from the battery is indicated by the arrows 37.

95

Starting from the battery the circuit leads through conductor 38, series field 18, conductor 39, through the armature windings connected to commutator 10, through conductor 40, thence through conductor 41, switch arm 30, contact 33 and conductor 42, back to the opposite side of the battery. This connects one set of armature windings and the series field directly across the battery, so that this part of the apparatus acts

100

105

as a series motor. The other set of armature windings is connected across the battery through the conductor 38, series field 13, conductor 43, switch arm 32, conductor 44, 5 thence through the armature windings connected to commutator 11, conductor 45, contact 34, and switch arm 31, thence through conductor 41, switch arm 30, contact 33, and conductor 42, back to the opposite side of 10 the battery. Of course these sets of armature windings connected to the commutator 11 also act under the influence of the series field 13 as well as the shunt field 12 the switch 20 being closed.

15 With the switch in this position, energy is furnished by the battery to start the engine, the motor producing sufficient torque with these connections, for this purpose. After the engine has attained sufficient speed the 20 switch arms 30, 31 and 32 are thrown in the position indicated in dotted lines, so that the dynamo is connected across the battery through the following circuits, the direction of charging current being indicated by the arrows 46. From the negative side of the battery, through conductor 42, conductor 47, coil 19, main switch 17, conductor 48, thence through the armature windings connected to commutator 11, 25 thence through conductor 44, contact 35, switch arm 31, conductor 40, thence through armature windings connected to commutator 10, thence through conductor 39, series field 13 and conductor 38, back to the opposite 30 side of the battery.

It will be noticed that with this arrangement of connections the current in the series field is in the reverse direction, so that it opposes the shunt field 12 and acts as a 40 regulating field for maintaining the current output of the generator substantially constant. When the engine and dynamo attain sufficient speed to charge the battery the main switch 17 closes under the action of voltage coil 18. Current passing through the coil 19 charging the battery or supplying the lamps, aids the coil 18 in maintaining the switch closed. Upon a decrease in 45 speed and voltage of the dynamo, if the battery tends to send current back through the generator, the current in coil 19 opposes the current in coil 18 and causes the main switch to open.

By arranging the sets of armature windings in series sufficient voltage is produced 50 to charge the battery and yet a sufficient torque is produced upon connecting these armature windings in parallel to start the engine with a small battery voltage. It is 55 not necessary to the broader aspects of my invention that both sets of armature windings be upon the same magnetic structure, as obviously more or less satisfactory results may be obtained by other arrangements.

60 However, it is far better to have them upon

the same magnetic structure as more space is saved thereby.

In order that the engine may be more easily started and with less energy, I provide means for automatically relieving the 70 pressure within the cylinders 1-1 when it is desired to start the engine. For this purpose pet cocks 50 are provided which are designed to be opened upon throwing the switching arms 30, 31 and 32 to the position 75 shown in the full lines, that is, when it is desired to start the engine. For this purpose the link 36 is connected by means of bell crank lever 51 and links 52 and 53, with the valves of the pet cocks, to open same 80 when the switching arms are thrown, to start the engine. Obviously, any other suitable means or connecting devices may be provided whereby the pressure of the engine is relieved when it is desired to start the engine. Upon throwing the switch arms to the position shown in dotted lines the pet cocks 50 are closed so that the engine at 85 once picks up under its own power, so that it will drive the dynamo and charge the 90 battery.

Although I have described my improvements in great detail and with respect to one particular embodiment thereof, nevertheless I do not desire to be limited to such 95 details except as clearly specified in the appended claims since many changes and modifications may well be made without departing from the spirit and scope of my invention in its broader aspects.

Having fully and clearly described my improvements, what I claim as new and desire to secure by Letters Patent, is:

1. The combination of an internal combustion engine, a dynamo mechanically connected to the engine shaft, a storage battery in operative relation to the dynamo whereby energy may be transmitted from the engine to charge the battery and from the battery to start the engine, said dynamo 105 having two sets of armature windings, and switching means for connecting said sets of windings in series when charging the battery and in parallel when starting the engine and for relieving the pressure in the 110 engine cylinders when starting the engine.

2. The combination of an internal combustion engine, dynamo electric apparatus mechanically connected to the engine to drive the same and be driven thereby, a 115 storage battery in operative relation to said dynamo electric apparatus whereby energy may be transmitted from the engine to charge the battery and from the battery to start the engine, said dynamo electric apparatus 120 having two sets of armature windings, and switching means for connecting said sets of windings in series when charging the battery and in parallel when starting the engine, electric ignition devices for the en- 125 130

gine, a distributor for said ignition devices, and connections for supplying the distributor from the dynamo with alternating current when the armature windings are connected in series.

3. The combination of an engine, dynamo electric apparatus mechanically connected to the engine to drive the same and be driven thereby, a storage battery in operative relation to said dynamo electric apparatus whereby energy may be transmitted from the engine to charge the battery and from the battery to start the engine, said dynamo electric apparatus having two sets 15 of armature windings, a shunt field winding and a series field winding, and switching means for connecting said sets of armature windings in series when charging the battery and in parallel when starting the engine, said series winding being so connected as to oppose the shunt winding when charging the battery and to aid the shunt winding when starting the engine.
4. The combination of an internal combustion engine, a dynamo mechanically connected to the engine to drive the same and be driven thereby, a storage battery in operative relation to said dynamo whereby energy may be transmitted from the engine 25 to charge the battery and from the battery to start the engine, said dynamo having two sets of armature windings, a shunt field winding and a series field winding, and switching means for connecting said sets 30 of armature windings in series when charging the battery and in parallel when starting the engine, said series winding being so connected as to oppose the shunt winding when charging the battery and to aid the 35 shunt winding when starting the engine.
5. The combination of an engine, dynamo electric apparatus mechanically connected to the engine to drive the same and be driven thereby, a storage battery in operative relation to said dynamo electric apparatus whereby energy may be transmitted from the engine to charge the battery and from the battery to start the engine, said dynamo electric apparatus having two sets 40 of armature windings, switching means for connecting said sets of windings in series

when charging the battery and in parallel when starting the engine, means for relieving the gas pressure in the engine cylinder or cylinders, and means whereby operation 55 of said switching means causes the operation of said pressure-relieving means.

6. The combination of an internal combustion engine, a dynamo mechanically connected to the engine to drive the same and be driven thereby, a storage battery in operative relation to said dynamo whereby energy may be transmitted from the engine to charge the battery and from the battery to start the engine, said dynamo having 60 two sets of armature windings, switching means for connecting said sets of windings in series when charging the battery and in parallel when starting the engine, means for relieving the gas pressure in the engine 65 cylinder or cylinders, and connections from said switching means to said pressure-relieving means whereby, when the switching means is operated to connect the sets of armature windings in parallel, the pressure- 70 relieving means is operated to relieve the pressure in the cylinder or cylinders of the engine.

7. The combination of an internal combustion engine, dynamo electric apparatus 80 mechanically connected to drive the engine and be driven thereby, a storage apparatus in operative relation thereto, whereby energy may be transmitted from the engine to charge the storage apparatus, and from 85 the storage apparatus to start the engine, said dynamo electric apparatus having two sets of armature windings, and switching means for connecting said sets of windings in series when charging the storage apparatus, and in parallel when starting the 90 engine, and said dynamo having a shunt and series field winding, which act cumulatively when starting the engine.

In testimony whereof, I have signed my 95 name to this specification, in the presence of two subscribing witnesses.

JOHN W. JEPSON.
